UNITED STATES PATENT OFFICE.

DAVY VANCE SICKMAN, OF DENVER, COLORADO.

COAL-MINING MACHINERY.

No. 838,469.

Specification of Letters Patent.

Patented Dec. 11, 1906.

Application filed November 23, 1903. Serial No. 182,307.

To all whom it may concern:

Be it known that I, DAVY VANCE SICKMAN, a citizen of the United States, residing at Denver, in the county of Denver and State of Colorado, have invented certain new and useful Improvements in Coal-Mining Machinery; and I do hereby declare the following to be a full, clear, and exact description of the invention, such as will enable others skilled in the art to which it appertains to make and use the same.

The invention relates generally to an improvement in coal-mining machines, and specifically to a power-operated coal puncher or pick wherein electricity serves as the motive power in lieu of the pneumatic devices now in general use.

The main object of the invention is to provide suitable mechanism for engaging and automatically releasing the ram or piston carrying the pick, whereby to render more effective the motive power in compressing the ram-driving springs.

Another object of the invention is to so construct and arrange the several parts of the machine that the same may be economically produced and operated and durable and effective in use.

With these objects in view my invention consists in the details of construction and combinations of parts hereinafter described and claimed, particular reference being had to the accompanying drawings, in which—

Figure 1 is a central longitudinal section, partly in elevation, of my improved mining-machine. Fig. 2 is a plan, partly in section, of the same. Fig. 3 is a section on line $x-x$, Fig. 2. Fig. 4 is a sectional view on line $y-y$, Fig. 1, showing in plan the cam-plates for operating the releasing mechanism, the lever-rollers being shown in normal positions in full lines and in operative positions in dotted lines. Fig. 5 is a horizontal sectional view taken through the cross-head and ram, the parts being in disengaged position. Fig. 6 is an enlarged sectional view showing the ram-driving springs and the guide-rods for the ram-head. Fig. 7 is a vertical sectional view taken through the cross-head, the ram being in place and the operating-levers being shown in elevation.

The machine is supported from a metal frame comprising castings of definite form having covers to inclose the working parts. As the form of the frame will differ to suit different requirements, no particular descrip-

tion of such is necessary herein, it being simply noted as a frame 1.

An electric motor 2 is suitably mounted at the rear end of the frame, to the armature-shaft of which is fixed a bevel-pinion 3. A bevel-gear 4, centrally fixed on a shaft 5, mounted in bearings 6, rising from frame 1, is suitably driven by pinion 3. The ends of shaft 5 beyond the frame carry spur-pinions 7, arranged to mesh with and drive spur-gears 8, fixed on a transverse shaft 9, supported in suitable bearings 10, as shown.

Each of the gears 8 is provided with a crank-pin 11, to which is secured one end of a connecting-rod 12, the opposite end of which is secured to a cross-head 13. The cross-head, preferably in two equal vertical sections bolted together, is mounted to reciprocate in the main frame between guides 14. The remote face of each cross-head section is provided with a wrist-pin 15, projecting beyond the frame 1 and receiving the end of the connecting-rod 12. The cross-head is formed with a central longitudinal opening 16 and with horizontally-arranged transverse passages 17, communicating with opening 16, a vertical opening 18 extending through the cross-head on each side the opening 16, said vertical openings communicating with the passages 17, as clearly shown in Fig. 7.

A toothed dog 19 is mounted for movement in each of the passages 17, the teeth of the dogs being on the proximate faces—that is, toward the opening 16. Springs 20, seated in recesses 21 in each of the dogs and bearing against the walls of passages 17, tend to hold the dogs normally at the limit of inward movement. Levers 22, pivotally supported at their upper ends in ears 23, projecting from each cross-head section, extend downward loosely through the openings 18 of the cross-head, passing through suitable openings 24 in the dogs 19. The lower ends of the levers extend below the cross-head and are provided with rollers 25, as shown.

An auxiliary frame 26 is secured to the main frame 1, being longitudinally slit at its free end, as at 27, a clamping-bolt 28 serving to compress the slit end when desired. A bushing 29, preferably slotted, is held in the free end of frame 26, the wear in which is compensated for by a tightening of the clamping-bolt 28. The piston or ram 30 is operative through the bushing 29, extending rearward through opening 16 of the cross-head, being supported in suitable bearings. Contiguous

the bushing 29 the ram is formed with longitudinal grooves 31, arranged to receive projecting ribs 32, formed interiorly of the bushing, with the result to prevent the rotation of the ram in operation. The ram at its point of passage through the cross-head is provided with toothed segments 35, one at each side of the ram and positioned to be engaged by the dogs 19. The cut of the teeth of the segments and dogs is such as to present the effective working plane toward the rear, so that the dogs will engage and hold the segments when the dogs are moving in a rearward direction, but will slip over the teeth of the segments without holding engagement when moving in a forward direction. A collar 36 is secured on the ram immediately forward of the segments 35, and encircling the ram and held between the collar and an inward extension 37 of frame 26 is a recoil-spring 38. The rear end of the ram is provided with a rectangular head 39, preferably screwed onto a reduced end of the ram. A bearing-head 40 is securely fastened to the main frame directly beneath the motor 2 and in horizontal alignment with the ram-head 39. Guide-rods 41, secured in head 40 and passing loosely through openings 42 in the ram-head, are encircled by springs 43, which latter are compressed between the ram-head and the bearing-head in the operation of the machine and serve to drive the ram forward to its work.

To operate the releasing mechanism—that is, to disengage the dogs 19 and segments 35—I provide cam-plates 44, pivoted to frame 1 at the limit of rearward movement of the cross-head, each cam-plate serving to operate one of the dogs through the medium of its lever 22. The cam-plates, two in number, have divergent outer cam edges 45 and contiguous parallel edges 46, between the latter of which a wedge-plate 47 is arranged to enter, with the result to force said edges apart and alter the angle and distance from a fixed point of the outer or cam edge 45 of the plates 44. The wedge-plate is slidably held to frame 1 by a bolt 48, whereby to adjust the wedge-plate to hold the cams in a desired position. The rear ends of the cam-plates are to be locked in adjusted position by screw-bolts 49, as seen in Fig. 4. The frame is mounted upon wheels 50 and moved by handles 51, pivotally secured to the sides of the frame contiguous the motor 2 and adjustable as to height through a slot 52 and bolt 53, as shown in Fig. 1.

The parts being in the positions indicated in Fig. 1, the operation of my improved coal-puncher is as follows: The power of the motor forces the cross-head 13 in a forward direction, the dogs 19 overriding the toothed segments 35 of the ram. At the limit of the movement the dogs, through effect of springs 20, are forced into gripping or holding engagement with the segments, and on a return

movement of the cross-head the ram is forced toward the rear, gradually compressing springs 43. At a proper point in the travel of the cross-head the rollers 25 of levers 23 contact with and ride down the cam edges 45 of cams 44, forcing the levers outward and disengaging the dogs 19 and toothed segments 35, permitting the springs 43 to drive the ram forward with a force sufficient to render effective the tool 34. The capability of adjustment of the cam edges of the cam-plates through operation of the wedge-plate 45 permits the disengagement of the dogs and segments at various points in the travel of the cross-head, as will be evident, thus giving the operator control of the strength of the stroke of the ram, as a quick disengagement of the dogs and segments will of course operate the ram under a less tension of the springs 43 than if the disengagement took place only at the limit of movement of the cross-head. If the machine should be so placed that the operative surface will not receive the full strength of the force of the ram, the recoil-spring 38 will receive and absorb the shock, thereby preventing damage or strain to the machine.

In devices of the character heretofore known the operating-springs are compressed by direct movement of cams or cranks, thereby limiting the length of stroke, as a large sweep cam or crank would take up the power of the motor and but little power would be available to compress the springs. A distinction is to be noted in this construction in favor of my device, in that I use the full power of the motor in compressing the springs, dispensing with the use of large cams or cranks. It will be further noted that as the crank connection approaches a line drawn through its axis its throw is gradually diminished, the completion of the compression of the springs being about complete, giving the crank-arm greater power just as it is needed.

The above description and the drawings herewith are illustrative of the preferred embodiment of my invention, and I desire it understood that I consider all mechanical changes and variations as fully within the scope of my invention.

What I claim as new is—

1. In a coal-mining machine, a ram carrying a tool, springs for driving the ram forward, an electric motor, means continuously operated by the motor in the direction of movement of the ram, and independently-operated clutches to engage the ram at diametrically opposite points and moving the ram to compress the springs.

2. In a coal-mining machine, a frame, a motor mounted thereon, a ram carrying a tool, springs for driving the ram, a cross-head reciprocated by the motor, independently-operated toothed dogs carried by the cross-

head, toothed segments carried by the ram and arranged to be engaged by the dogs to move the ram, levers operable to disengage the dogs and segments, and means to automatically operate the levers.

3. In a coal-mining machine, a frame, a motor mounted thereon, a ram carrying a tool, springs for driving the ram, a cross-head reciprocated by the motor, independently operated toothed dogs carried by the cross-head, toothed segments carried by the ram and arranged to be engaged by the dogs to move the ram, levers connected to the dogs, cams to operate the levers to disengage the dogs and segments, and means for spreading the cams to adjust them.

4. In a coal-mining machine, a frame, a motor mounted thereon, a ram carrying a tool, springs for driving the ram, a cross-head reciprocated by the motor, toothed dogs carried by the cross-head, toothed segments carried by the ram and arranged to be engaged by the dogs to move the ram, levers connected to the dogs, cams to operate the levers to disengage the dogs and segments, and a wedge-plate to adjust the cams.

5. In a coal-mining machine, a reciprocating cross-head, a ram movable through the cross-head, means interiorly of the cross-head operative at its forward limit of movement to engage the ram, means to disengage the ram and cross-head at a predetermined point in the rearward movement of the latter, and means to project the ram forward when released from the cross-head.

6. In a coal-mining machine, the combination with a motor, a continuously-operated cross-head connected with and receiving power from the motor, a ram carrying a tool, means connecting the cross-head and ram for

moving the latter in one direction, means operated by the ram when the latter is connected to the cross-head for storing the power to drive the tool in reverse direction, and means disconnecting the ram and cross-head. 45

7. In a coal-mining machine, a ram carrying a tool, means for driving the ram and tool forward, a continuously-operated cross-head having mechanism for engaging the ram when the cross-head is at its forward stroke, 50 the return movement of the cross-head, and ram compressing the means for driving the ram and tool forward, and means disconnecting the ram and cross-head.

8. In a coal-mining machine, a ram carrying a tool, springs for driving the ram forward, a motor, means continuously operated by the motor in the direction of movement of the ram, said means engaging and moving the ram to compress the springs, and means dis- 60 engaging the continuously-operated means and the ram.

9. In a coal-mining machine, a movable ram carrying a tool, a cross-head continuously reciprocated under power, means connecting 65 the ram and cross-head, automatically-operated means for disengaging the ram and cross-head, and a power-spring placed under tension by the ram when the latter is connected with the cross-head and acting on the 70 ram to drive the latter forward when released from the cross-head.

In testimony whereof I have signed my name to this specification in the presence of two subscribing witnesses.
